UNITED STATES PATENT OFFICE.

JOSEPH J. WHITE, OF PROVIDENCE, RHODE ISLAND, ASSIGNOR TO J. J. WHITE MANUFACTURING COMPANY, OF PROVIDENCE, RHODE ISLAND.

DESIGN FOR A RING OR SIMILAR ARTICLE OF MANUFACTURE.

Application filed January 8, 1927. Serial No. 20,311. Term of patent 3½ years.

To all whom it may concern:

Be it known that I, JOSEPH J. WHITE, a citizen of the United States, residing at Providence, in the county of Providence and State of Rhode Island, have invented a new, original, and ornamental Design for Rings or Similar Articles of Manufacture, of which the following is a specification, reference being had to the accompanying drawing, forming a part thereof.

A salient feature of the design consists of the forms and group relationship of the settings other than the gems in the diagonal bars.

Figure 1 is a top plan view of a ring embodying my new design.

I claim:

The ornamental design for a ring or similar article of manufacture, as shown and described.

JOSEPH J. WHITE.
